UNITED STATES PATENT OFFICE.

GEORGE A. FARRELL, OF ALTOONA, PENNSYLVANIA.

METALLIC TIE.

1,139,855.

Specification of Letters Patent. Patented May 18, 1915.

Application filed March 25, 1914. Serial No. 827,149.

To all whom it may concern:

Be it known that I, GEORGE A. FARRELL, a citizen of the United States, residing at Altoona, in the county of Blair and State of Pennsylvania, have invented certain new and useful Improvements in Metallic Tires, of which the following is a specification.

This invention relates to railroad ties of the metallic form, and has for its primary object improved means for imparting resiliency to the rigid metallic structure as heretofore used and found to be deficient in this particular.

Another object of this invention is to provide a position for the resilient element, such, that the ballast of the roadbed, rain, snow or water will in no way interfere with the vertical movement of the top of the tie to which the rails are secured.

Another object of the invention is to provide a stationary body piece for the tie, and a movable top piece which are adapted to be held in the proper spaced relation by the resilient element.

A still further object of this invention is to provide ample rail securing means, as well as to provide for the necessary grip on the roadbed, thus preventing longitudinal and transverse movements of the tie with reference to the roadbed.

With these and many other objects in view, which will be more readily apparent, as the nature of the invention is better understood, the same consists of the novel construction, combination and arrangement of parts as will be hereinafter fully pointed out, illustrated and claimed.

It will be readily understood that this invention is quite susceptible to a wide range of structural modification without departing from the spirit or scope of the invention, but a preferred and thoroughly practical embodiment is shown in the accompanying drawings, in which—

Figure 1, is a plan view of the present invention showing the rail in position on the tie. Fig. 2 is a longitudinal sectional view.

Similar reference numerals refer to similar parts throughout the several figures of the drawings.

In carrying out this present invention, no change is contemplated in the usual form of rail or in the gage of track, while the length and width of the improved tie follow very

closely that of the standard wooden tie, so as to make the substitution of the new for the old a comparatively easy task.

In the construction of this improved tie, it is preferable to make the bottom, or ballast gripping portion 10 and the rail carrying portion 11, in two separate pieces and interpose between the upper and lower portions 10 and 11 respectively, the resilient element 12 which, preferably, consists of a plurality of helical springs 13 and 14, one positioned inside the other as clearly shown in Fig. 2, of the drawings.

The resilient element 12 is positioned in the cup-shaped receptacle 15, which is, preferably, formed integral with the face 16 of the tie body 10. The receptacle 15 is preferably round and made to aline with and to engage the coöperating cup-shaped socket 17 formed integral with the top of the tie 11. The coöperation of these cup-shaped sockets provides an ideal housing of the resilient element 12, and readily excludes all foreign substance from the resilient member cavity.

It will be observed that the free height of the springs is slightly in excess of the depth of the cup-shaped socket, this being a requirement such, that the top and bottom members do not lock or impinge upon one another, when the wheel-load is upon the tie under consideration.

In addition to being provided with a downwardly turned socket 17, the top member 11 is provided with rail clamping means which consist essentially of a plurality of rail engaging elements 18, held to the tie by suitable bolts 19, which are adapted to pass through the bolting flange 20 of the tie.

The top member 11 of the tie is preferably made with webs 21, which serve materially to strengthen the top surface 22 and make a rigid construction.

In addition to the bottom 10 being provided with the spring sockets, it is also provided with an inverted saucer-shaped ballast engaging lip 23, which preferably extends around the periphery of the base. In addition to the lip 23, there is provided a transverse web 24 which serves to strengthen the lip on both sides, as well as to firmly grip the ballast, thus preventing tie displacement.

Without further description and elabora-

tion, it is believed that the many advantages of this device will be readily apparent, and—

What I claim and desire to be secured by Letters Patent is—

- 5 1. A metallic railway tie comprising a lower ballast engaging member having upwardly extending socket portions located adjacent the opposite ends thereof, a rail carrying member having oppositely located socket portions telescoping with the said socket portions on the base member, and springs arranged in the sockets of the ballast engaging member adapted to yieldingly support the rail carrying member.
- 10 2. A metallic railway tie including a bottom ballast engaging member of dished formation and having a central transverse bracing web, said ballast engaging member also
- 15

having socket members formed therewith and located adjacent the opposite ends thereof, a top rail carrying member having a vertical and oppositely disposed lateral reinforcing webs, and also having socket members formed at each end and adapted to telescopically receive the socket members on the ballast engaging member, and springs arranged in the sockets of the ballast engaging member adapted to yieldingly support the rail carrying member.

In testimony whereof I affix my signature in presence of two witnesses.

GEORGE A. FARRELL.
